RESERVOIR TYPE RULING PEN

Filed June 20, 1950

UNITED STATES PATENT OFFICE

2,619,069

RESERVOIR TYPE RULING PEN

Apolonio V. Almazar, Pleasantville, N. Y.

Application June 20, 1950, Serial No. 169,109

1 Claim. (Cl. 120—42.6)

1

This invention relates to a drawing or ruling pen.

The invention comprehends a drawing or ruling pen of the reservoir type having a discharge opening for feeding ink to ink-applying blades together with means for freeing the discharge opening of encrusted or dried ink.

Another object of the invention is to provide a feed tube which is connected with the body of the pen for movement axially thereof and through which protrudes a fixed central stem for insuring a ready flow of the ink through the discharge opening in the feed tube and for freeing the said opening from encrusted or dried ink by the axial movement of the feed tube.

Still another object of the invention is to provide a reservoir type pen with ink-applying blades which are swingably and detachably associated with the forward end of the pen for facilitating cleaning thereof.

Still another object of the invention is to provide a drawing or ruling pen of said character which embodies an improved construction and arrangement of parts by which the ink is forcibly fed to the applying blades and by which the parts may be readily freed of encrusted ink.

With the foregoing and other objects in view, reference is now made to the following specification and accompanying drawings in which the preferred embodiment of the invention is illustrated.

In the drawings:

Fig. 1 is an enlarged vertical sectional view through a drawing or ruling pen of the reservoir type constructed in accordance with the invention.

Fig. 2 is a view in elevation thereof showing the ink-applying blades swung into angular relation therewith.

Fig. 3 is a cross-sectional view taken approximately on line 3—3 of Fig. 1.

Fig. 4 is a similar view taken approximately on line 4—4 of Fig. 1.

Fig. 5 is a fragmentary sectional view showing the filler sack in twisted formation.

Fig. 6 is a cross-sectional view taken approximately on line 6—6 of Fig. 1.

Referring to the drawings by characters of reference, the pen includes a cylindrical barrel 10 in which is arranged an elastic tubular filler sack 11 constituting an ink reservoir. The filler sack is cemented or otherwise affixed at its outer end to a bell shaped member 12 having a shank 13 threadedly engaging an interiorly threaded stud 14 so as to clamp the outer end of the sack be-

2

tween the same and the bell shaped member 12 to thereby close the outer end of the sack. The stud 14 protrudes through a bushing 15 threadedly secured to the outer end of the barrel 10 and a head 16 swivelly mounted on the outer end of the bushing 15 is secured by a screw 17 to the protruding end of the stud 14 for effecting twisting of the sack. The bushing 15 is formed with an annular recess 18 in which the inner ends of studs 19 secured in openings in the cap 16 are slideable to permit of swivel turning movement of the head 16 on the bushing 15.

The forward end of the sack is cemented or otherwise secured about the outer periphery of a tubular member 22 which is threadedly secured at its forward end in an interiorly and exteriorly threaded bushing 23. The said bushing is threadedly secured in the forward end of the barrel 10 with the reduced forward end 24 of said bushing protruding therefrom. A forwardly tapering feed tube 25 is threadedly engaged in the protruding end 24 of said bushing and the same is provided with a longitudinally extending feed duct 26 formed as a continuation of the opening 27 in the tubular member 22. A tapered shank 28 having an interiorly threaded inner end is secured on the projecting reduced end of said bushing with the feed tube projecting forwardly therethrough. The feed tube is provided with an annular flange 30 which is arranged in an internal annular recess 31 formed in the shank forwardly of the protruding end of the bushing 23 for limiting the axial movement of said feed tube. When the feed tube is in normal forward position the flange 30 thereof is disposed in abutting engagement against the annular shoulder 32 formed by the reduced internal diameter of the forward end 33 of the shank 28, and when the tube is moved inwardly by turning thereof on the threaded engagement with the protruding end of said bushing, the flange abuts against the end edge 34 of said bushing.

An annular cushion element 36 is located between the inner end of the feed tube 25 and the shoulder 37 of the bushing 23 which shoulder is formed by the inwardly directed flange 38. The cushion element 36 is formed of compressible resilient material such as rubber composition which will compress and expand with the inward and outward movement of the feed tube. Arranged centrally within the feed duct 26 of the feed tube 25 and extending longitudinally thereof is a tapered stem 39 which is formed integrally with the tubular member 22 and is provided with a reduced terminal 40 protruding through the dis-

charge orifice 41 in the outer end of the tube. The ink flows from the filler sack 11 through the opening 27 in the tubular member 22 and thence through the discharge duct 26 about the stem 39 and is discharged through the orifice 41 onto a bar 42 located between ruling blades 43 and 44 for conducting the ink from the orifice to the outer ends of said blades.

It will be understood that the feed tube 25 has rotary motion with reference to the stem 39 by the turning of the tube on its threaded engagement with the projecting end 24 of the bushing 23. This will effect movement of the feed tube longitudinally of the stem 39 until the annular flange 30 is disposed in abutting engagement with the end edge 34 of the bushing 23. The inward movement of the feed tube will cause the reduced end 40 of the stem to project a greater distance through the orifice 41 so as to break up and dislodge any encrusted ink which may solidify in the discharge orifice. The relative movement of the feed tube with reference to the stem 39 will also break up and dislodge any ink which has solidified in the duct 26 so that the ink will flow freely through the discharge orifice. The ink may be forced through the duct 26 by turning of the head 16 so as to twist the filler sack 11 as shown in Fig. 5 of the drawings. The pressure thus created in the duct 26 will force the dislodged dried or encrusted ink through the discharge orifice 41.

The ruling blades 43 and 44 are integrally connected to a base portion 45 which is of arcuate formation subtending approximately 260° as shown in Fig. 6 of the drawings. The base 45 is formed with downwardly directed terminals 46 at each side which are provided with inwardly directed lugs 47 engaging in sockets 48 in the outer face of the feed tube 25 to permit of swinging movement of the blades from aligned relation with the pen to an angular relation therewith as shown in Fig. 2 of the drawings for cleaning the inner faces of the blades. The blades 43 and 44 are normally disposed in spaced relation by the spring tension thereof and the blade 43 is provided with a screw stud 49 which protrudes through an opening in the blade 44 and is engaged by a nut 50 for moving the blades inwardly into the proper spaced relation for ruling the desired width of line. The base portion 45 clampingly engages the tapered portion of the feed tube 25 when in operative position thereon but the same is sufficiently resilient to permit of expansion thereof for movement out of aligned relation with the feed tube. The bar 42 is affixed to the shank of the stud 49 to dispose the same in position between the blades so as to receive ink discharged through the orifice 41 for conducting the same to the outer end of the blades. An opening 52 is provided in the wall of the feed tube 25 which opens into the feed duct 26 adjacent the forward end thereof and which is normally closed by a closure member 53 pivoted to the feed tube as at 54.

In order to fill the sack 11 with ink, the head

16 is rotated to twist and tension the sack so as to expel air therefrom, as illustrated in Fig. 5 of the drawings. When the head 16 is released, the tension in the sack 11 will cause the same to unwind and produce a suction in the passageway 26 so as to draw ink upwardly therein through the orifice 41. For this purpose the blades 43 and 44 are swung to one side, as illustrated in Fig. 2, and the reduced end of the feed tube immersed in ink.

The ink may be forcibly fed through the feed duct 26 by turning the head 16 to twist the sack 11. In order to provide for a gravity flow of the ink the closure 53 may be opened to allow air to enter the feed duct 26 which will rise upwardly into the sack 11. Whenever required the feed tube 25 may be moved inwardly on its threaded engagement with the bushing 23 so as to project the reduced end 40 of the stem 39 farther through the orifice 41 to thereby break up and dislodge any encrusted ink in the duct 26 of the feed tube.

What is claimed is:

In a reservoir type ruling pen, a barrel, a tubular sleeve secured to said barrel and projecting forwardly therefrom, a tubular shank secured to the projecting end of said sleeve, a feed tube projecting through the forward end of said shank and threadedly engaging said sleeve and having a discharge orifice in its forward end; a tubular member carried by said sleeve inwardly thereof and having a central stem extending longitudinally of the feed tube with the forward end thereof protruding through the discharge orifice, a compressible annular packing arranged at the inner end of said feed tube and said feed tube being movable longitudinally with reference to the stem by turning movement of said feed tube on said tubular shank for breaking up and dislodging encrusted ink in the discharge orifice, ruling blades pivoted to said feed tube and projecting forwardly thereof, and a bar located between said blades with the outer end thereof disposed adjacent said discharge orifice and the forward end thereof disposed adjacent the tips of the blades for receiving ink fed through said orifice and for conducting the same to the forward ends of the blades.

APOLONIO V. ALMAZAR.
